The ornamental design for an automotive electronics enclosure with three outlets, as shown.

DESCRIPTION

FIG. 1 is a front left side perspective view of the present automotive electronics enclosure with three outlets design; FIG. 2 is a front view of FIG. 1 of the automotive electronics enclosure with three outlets;

FIG. 3 is a rear view of FIGS. 1 and 2 of the automotive electronics enclosure with three outlets;

FIG. 4 is a top view of FIGS. 1 to 3 of the automotive electronics enclosure with three outlets;

FIG. 5 is a bottom view of FIGS. 1 to 4 of the automotive electronics enclosure with three outlets;

FIG. 6 is a left side view of FIGS. 1 to 5 of the automotive electronics enclosure with three outlets; and,

FIG. 7 is a right side view of FIGS. 1 to 6 of the automotive electronics enclosure with three outlets.
